UNITED STATES PATENT OFFICE.

D'ORSAY McCALL WHITE, OF INDIANAPOLIS, INDIANA, ASSIGNOR TO LA FAYETTE MOTORS COMPANY, OF INDIANAPOLIS, INDIANA, A CORPORATION OF DELAWARE.

OIL-PUMP FOR INTERNAL-COMBUSTION ENGINES.

1,366,227.

Specification of Letters Patent. Patented Jan. 18, 1921.

Application filed January 2, 1920. Serial No. 348,932.

To all whom it may concern:

Be it known that I, D'ORSAY McCALL WHITE, a subject of the Kingdom of Great Britain, and a resident of Indianapolis, 5 county of Marion, and State of Indiana, have invented a certain new and useful Oil-Pump for Internal-Combustion Engines; and I do hereby declare that the following is a full, clear, and exact description there- 10 of, reference being had to the accompanying drawings, in which like numerals refer to like parts.

The object of this invention is to provide in an internal combustion engine or the like 15 an oil pump of the gear type and arrange the same in a novel and improved manner, whereby the driving gear of said pump will be carried by the engine shaft and the relief valve of the pump discharges upon 20 means associated with the main driving shaft and adjacent thereto for lubricating the same.

Other objects, such as the particular construction and arrangement of the relief 25 valve and relation thereof with respect to the pump and the particular construction of the pump itself, will be illustrated in the drawings and described in the following specification.

30 The full nature of the invention will be understood from the accompanying drawings and the following description and claims.

In the drawings, which are made a part 35 of this application, Figure 1 is a central sectional view of the crank shaft of an internal combustion engine or the like, the latter embodying the invention and other parts usually associated with the crank 40 shaft. Fig. 2 is a side elevation of the gear pump proper and the relief valve, taken on the line 2—2 of Fig. 1. Fig. 3 is an end view of the parts shown in Fig. 2. Fig. 4 is a sectional view similar to Fig. 45 2 and taken on the line 4—4 of Fig. 3. Fig. 5 is a side view of the parts shown in Fig. 2 and taken at right angles to Fig. 3. Fig. 6 is a sectional view of the gear pump taken on the line 6—6 of Fig. 4.

50 In the drawings 11 indicates the crank shaft of an internal combustion engine or the like, the same being rotatably mounted in a bearing 12 and a crankcase 13. Beneath the crankcase is positioned the usual 55 oil pan 14 provided with a suction supply

pipe 15 leading to the oil pump 16, the latter being shown mounted upon the shaft 11 and secured to the crankcase. Forwardly on said shaft and suitably secured thereon, as by a key 17, is a sprocket wheel 18, the 60 same driving a sprocket chain 19. Positioned above said crank shaft is a second shaft 20, commonly known as a cam shaft, for driving the timing mechanism 21 and a fan, not shown, by means of a sprocket 65 chain 22. The cam shaft is driven by the sprocket chain in any suitable manner. Communicating with said pump and operatively associated therewith is an outlet 23, said outlet communicating with suitable 70 conduits 24 by which the engine is lubricated. Herein the bearing 12 is shown provided with an opening 25, the same communicating with one of the conduits 24 for lubricating said bearing, the bearing being 75 herein shown supported by a suitable bracket 26.

The detailed construction of the pump and relief valve is shown in Figs. 2 to 6 inclusive. Within the pump housing 16 are 80 formed two annular communicating chambers 27 and 28 respectively in which closely fit two rotatable meshing gears, the driving gear 29 and the idle gear 30. The driving gear 29 is shown secured to the crank 85 shaft 11 by a key 31, whereby said gear is driven directly by said crank shaft.

The pump housing 16 is also provided with an inlet channel and port 32, the same communicating with the suction supply pipe 90 15, and a discharge port and channel 33, the latter communicating with the outlet 23. Herein the pump 16 is shown provided with a cover 34, the same being suitably secured thereto, as by bolts 35. As shown in Fig. 6, 95 the idle gear 30 is rotatably mounted in the housing 16 upon a hollow shaft 36, said housing also being provided with bushings 37 in which said shaft may rotate.

The gear pump is herein shown provided 100 with a relief valve, the body portion 38 communicating with the discharge outlet 33 and being secured thereto in any suitable manner, such as by the screw threaded connection 39, as shown in Fig. 4. The screw 105 threaded connection herein is shown provided with a valve seat 40. Adjacent thereto and within the body portion 38 is a ball relief valve 41. Slidable in said body portion and normally engaging said ball upon 110

the side opposite said valve seat is a semi-spherically faced follower 42. Said follower is provided on the opposite side with a spring seat 43, whereby said follower normally engages said ball and seats the latter upon the valve seat 40. The screw stem 44 is provided with a spring seat 45 against which the upper end of a spring 46 may contact, the lower end of said spring being secured upon the seat 43 of the follower, as described. A cap 47 is herein shown suitably secured in the body portion 38 by being screwed therein, and said cap is provided with a threaded central opening 48 in which the screw 44 is mounted. The screw 44 carries on its upper end a lock nut 49, the same locking the screw 44 in the adjusted position to the cap 47.

A relief chamber 50 within the body portion of said relief valve discharges directly into the front compartment of the engine. An outwardly extending discharging nipple 51, the same being provided with discharge ports 52, is included within the pressure system adjacent said relief valve in any suitable manner. Said discharge nipple projects forwardly over said pump and into the sprocket chain 19 above the sprocket wheel 18 to discharge oil over and upon the chain for lubricating the same.

The invention claimed is:

1. In an internal combustion engine the combination of a crank shaft thereof, a gear pump comprising a pair of meshing gears, and having one of said gears rigid with said crank shaft for rotation therewith, and a lubricating system connected with said pump for supplying lubricant to said engine. 35

2. In an internal combustion engine the combination of a crank shaft thereof, a gear pump comprising a pair of meshing gears, and having one of said gears rigid with said crank shaft for rotation therewith, and a relief valve for said pump discharging adjacent said shaft for lubricating other mechanism associated with said shaft. 45

3. In an internal combustion engine the combination with a crank shaft, and a gear pump operable by the shaft, of a lubricating system for supplying lubricant to said engine, and a discharge nipple positioned upon said pump to communicate with said pump independently of said lubricating system for discharging lubricant upon mechanism associated with said shaft, said nipple projecting forwardly of said pump. 50 55

In witness whereof, I have hereunto affixed my signature.

D'ORSAY McCALL WHITE.
